UNITED STATES PATENT OFFICE.

CLAUDIUS DORNIER, OF FRIEDRICHSHAFEN, GERMANY.

GIRDERS.

Application filed June 28, 1920, Serial No. 392,550, and in Germany November 17, 1917.

(GRANTED UNDER THE PROVISIONS OF THE ACT OF MARCH 3, 1921, 41 STAT. L. 1313.)

My invention relates to girders and more especially to girders with triangular framework for use in connection with light forms of construction. For the purpose of combining light weight with maximum power of resistance against the possibility of the girder collapsing either along the vertical or the horizontal plane, and further to prevent any lateral shift, there are employed in accordance with my present invention both for the flanges, as also for the web members, the grooves of which are essentially uniform in shape and disposed in the longitudinal direction of the girders. At 15 the assemblage points the grooves engage one in the other.

Girders of the kind described will be found superior to those hitherto in use by reason of their requiring but isolated rivet joints, capable of being effected by simplest means. Since merely a small number of individual members are required, which may be made without trouble and joined with ease, the said girder will be also found eminently suitable for production on a large scale, without the exactitude of each individual girder being thereby in the least impaired. One particular form of structure will prove specially suitable, in the case of 30 which the sections of the flange and web members transversely to the longitudinal direction of the girder represent each a succession of alternately narrow and broad U-shaped channels. For by these means, even in the case of larger widths of girder, it will be discovered that a relatively small number of channels will suffice for the purpose in hand, and these may therefore be obtained with all the more ease and with every exactitude desired by a longitudinal rolling process.

In the accompanying drawing, forming a part of this specification, are shown by way of example and in a purely diagrammatic manner two forms of construction embodying the subject matter of my invention.

In the drawings—

Fig. 1 is a side elevation of a girder,

Fig. 2 a cross-section along the line 2—2

50 in Fig. 1,

Fig. 3 a modified form of construction, and

Fig. 4 a longitudinal section of the web members employed therein in stretched con-

dition, as it presents itself before being applied to the flanges.

In the construction according to Figs. 1 and 2 the two flange plates A, B, as also the web member C are each provided with three narrow, upwardly bent, U-shaped longitudinal grooves a^1 , b^1 , c^1 , each alternating with two broader downwardly bent grooves. The dimensions are so chosen that the web member C as long as it is in stretched condition, if placed between the flange plates, would envelop with its grooves c^1 the corresponding grooves b^1 of the lower flange plate B, and, on the other hand, engage in the grooves a^1 of the upper flange plate A, which member, by the way, is very thin. 70 The member C, which as a whole is sinuously bent in a direction perpendicular to the centre plane of the plate, extends in zig-zag fashion as a triangular frame alternately within the two flange plates A and B, being 75 riveted together with said plates at the points of application and assemblage.

The modified form of construction according to Figs. 3 and 4 essentially differs from that above described merely by the fact of 80 the web faces of the narrow U-shaped channels and the common flange faces of the web members being cut out at the points of intersection, in correspondence with the bending angle of the grooves c^1 . As accordingly 85 only the faces c^2 of the broad grooves continue their course unimpaired, the bending required to produce the sinuosity of the trellis work is very much facilitated. As Figs. 3 and 4 show, the indentures alternately differ somewhat among each other, this depending whether the released ends of two adjacent groove portions c^1 , when the web faces c^2 are bent back, are caused to approach (c^3) or separate (c^4), in other words, 90 whether they are to serve for a connection to the lower flange plate B or to the upper flange plate A. To prevent the web faces c^2 from being fractured, the indentures are 95 rounded off at the corners.

I wish it to be understood that I do not desire to be limited to the exact details of construction shown and described, for obvious modifications will occur to a person skilled in the art.

I claim:

1. A sheet metal trellis girder comprising two cords and a web member extending

zig-zag fashion between and fixed to said cords, both said cords and said web member being formed with longitudinal corrugations, the corrugations of said web member being fitted at the points of contact in corresponding corrugations of said cords.

5. 2. A sheet metal trellis girder comprising two cords and a web member extending zig-zag fashion between and fixed to said cords,

both said cords and said web member being 10 formed with longitudinal corrugations, wide corrugations alternating with narrow ones, the corrugations of said web member being fitted at the points of contact in corresponding corrugations of said cords. 15

In testimony whereof I affix my signature.

CLAUDIUS DORNIER.
